to Nicholson File Company, Providence, R. I.,
a corporation of Rhode Island

Application June 26, 1944, Serial No. 542,179

1 Claim. (Cl. 29—78)

1

My present invention relates to files and particularly to files of the type primarily intended to be manipulated manually in filing the surfaces of metallic or other objects.

The conventional file is relatively long and narrow and in the general case has a handle, or a tang or the like to which a handle may be secured, at one end only. The teeth of the file face its leading end, i. e., that end of the file which is most remote from the handle end and, when the file is being manipulated in the conventional manner, its user naturally moves it along a path, upon its working stroke, which has a forward component and a lateral component, the file moving forwardly or away from the operator and slightly to the left of the user's body, it being assumed that the operator is right-handed. The natural stroke, therefore, is to sweep sidewise to some extent, the file, however, being generally maintained throughout its movement with its axis in a constant direction, or substantially so. The natural working stroke is, therefore, such that not only one end of the file is constantly in advance of the other, and hence may be designated the leading end, but likewise one longitudinal edge of the file is constantly in advance of the other as the file moves slightly sidewise, such edge being conveniently designated the leading edge. In the design of the file which comprises the present invention full consideration has been given to the fact that the file when used will generally be manipulated with the natural stroke referred to and it has been so designed that its user will realize a number of novel and important advantages.

The improved file has, for instance, been so designed that it may perform both roughing and finishing operations upon a piece of work during a single file stroke. Thus the leading margin of the file, which is that portion of the file surface adjacent its leading edge, is different in design from the trailing margin, or that portion of the file adjacent the opposite or trailing edge thereof, the leading margin being so constructed as to accomplish a roughing effect and the trailing margin constructed so as to primarily perform smoothing operations. This is an advantage of considerable importance, insuring both rapid progress in filing and a finished appearance. The file teeth are likewise so arranged that the tendency of the file to chatter as it passes over a piece of work is greatly reduced, without sacrifice in the cutting ability of the file. Its design is such as to insure maximum removal of stock for a given pressure of the file

against the work and likewise so as to minimize the tendency of the file to become clogged with small portions severed from the work.

The teeth of the file are arcuate and each of the arcuate teeth is divided into arcuate lands by notches or serrations. While it has heretofore been proposed that a file may be provided with arcuate teeth and that such teeth may be notched, the present invention provides a novel and improved arrangement of notched arcuate teeth giving results not heretofore realized in the art. A preferred embodiment of the invention is illustrated in the accompanying drawings and will be described in detail. It will be appreciated by one skilled in the art that minor changes may be effected while at the same time maintaining the distinctive and advantageous features of the invention.

In the drawings:

20 Figure 1 is a plan view of the file;
Figure 2 is an edge view of the same;
Figure 3 is a plan view of a portion of the file, upon a scale which is larger than that used in Figure 1;

25 Figure 4 is a section on line 4—4 of Figure 3; and

Figure 5 is a section on line 5—5 of Figure 1.

The body of the file is of conventional shape and is indicated at 10 in the drawings, being relatively long and narrow and having parallel or substantially parallel longitudinal edges. The tang is indicated at 11. No handle is shown to be affixed to the tang, but it will be appreciated that the file may be provided with a handle if desired, or may be manipulated without the aid of a handle portion, as its operator chooses. The end of the file body which is remote from the tang 11 may be designated the leading end since the file teeth face this end and the file is pushed over the surface of the work, away from the operator and with this end in advance, when in normal use. In Figure 1 a portion of a piece of work is diagrammatically indicated at 12 and it will be understood that the work piece 12 must 30 of necessity be considered to be above the file, it being necessary to illustrate the file with its work-engaging surface uppermost instead of turned downwardly. Hence each area of the surface of the file will move, as the file is advanced on its natural working stroke, along some such path as indicated by the theoretically straight broken line A to be found in Figure 1. When so moving the axis of the file generally remains unchanged in direction, the file in each of 35 its positions being approximately parallel to its

previous and subsequent positions. The upper edge of the file, as it is illustrated in Figure 1, may therefore be designated its leading edge since this edge leads the other edge over the surface of the work during any lateral movement of the file, and the opposite edge may be designated the trailing edge.

The file teeth are indicated at 13 and are, as previously stated, arcuate, with their convex sides facing the leading end of the file. These teeth are preferably formed by milling and the forward face of each tooth, indicated at 13a, may advantageously be disposed at substantially a right angle to the plane of the file body. The rear face 13b of each tooth is preferably disposed at an acute angle to the plane of the file. The centers about which the arcuate teeth are generated are located to one side of the central longitudinal axis of the file, in the case of the file illustrated the centers being located along the leading edge of the file. With the tooth centers so located the angle between the leading edge of the file and a tangent to an arcuate tooth, at the point where such arcuate tooth terminates at such leading edge, is substantially a right angle. From the leading edge each arcuate tooth curves rearwardly of the file as shown and, where the tooth terminates at the trailing edge of the file the angle between such trailing edge and a tangent to the tooth at that point is approximately 37°, as shown in Figure 3 of the drawings.

Each file tooth is divided by a plurality of notches into a plurality of arcuate lands and the notches and lands may be clearly seen in Figures 4 and 5, the notches being indicated at 13c and the individual arcuate lands at 13d, 13e, 13f, 13g, 13h and 13i. In this and other figures of the drawings the leading edge of the file is indicated by the numeral 15 and the trailing edge by the numeral 16. The notches 13c are V-shaped and the walls of each meet at an angle of substantially 45°. The straight line bottom of each notch, which is the line of intersection of the side walls of the notch, indicated at 13k, is disposed at an angle of approximately 14° to the major axis of the file and, as will be observed in Figures 1 and 3, the inclined notches are arranged in rectilinear series, the leading notch of each series being at or closely adjacent the leading edge of the file and the rearmost or terminal notch of each series being adjacent the trailing edge of the file.

Each rectilinear series of notches begins at a point immediately adjacent the leading edge, or the leading end, of the file and extends rearwardly from that point toward the handle end of the file, each series making an angle of preferably 14°, as will the walls and straight line bottoms of individual notches, if prolonged, with the longitudinal axis of the file. In the drawings the several series of notches are shown to be disposed in exact parallelism and to be equidistantly spaced. This arrangement is desirable but, without departure from the invention, slight variations may be made in order to more particularly adapt the file to the performance of filing operations of different character.

In any event each arcuate tooth of the file is divided into arcuate but shorter portions, or lands. Where the series of notches are equidistantly spaced from each other, and are disposed in parallelism, the lands will vary in length, as shown in Figure 5, those lands toward the leading edge of the file being relatively short and the other lands increasing in length as the trailing

edge of the file is approached. Preferably the notches are cut after the arcuate teeth have been formed and the cutting operation may advantageously be performed by milling, broaching, grinding, or other suitable method.

In one form of file which has been shown to be highly efficient in operation twelve arcuate teeth are provided for each inch of length and the terminal ends of each tooth are spaced three-eighths of an inch apart, measured axially of the file, which is one inch wide. With a file of this width, and where the tooth radius is one and five-eighths inches, which is a preferred radius, the distance between each rectilinear series of notches and the adjacent series may be advantageously $\frac{1}{2}$ of an inch. The teeth are not notched entirely to the bottom, as clearly shown in Figures 4 and 5, although the notches may be made deeper if desired. In the general case it is only necessary to provide relatively shallow notches in order to accomplish the desired objectives.

When the file is in operation in the intended manner there will be a large number of teeth in contact with each area of the work, as may be readily perceived from an inspection of Figure 1, and the contact with the work, simultaneously, of a larger number of teeth renders the file much less likely to chatter than one in which the teeth are so arranged that a lesser number will be in contact with substantially the same area. This is an advantage of considerable importance particularly where, as in the case of the present invention, the number of teeth in contact with the work is made relatively large without sacrifice in tooth size and coarseness so that full cutting ability of the file is maintained.

Inasmuch as the lands of succeeding teeth are in echelon, or staggered with relation to each other, a maximum removal of stock from the work with a minimum pressure of the file against the work is realized. Possibility of clogging is reduced to a minimum because each tooth is broken up into a plurality of lands by the notches and a relatively short particle or piece of work is removed by each land. By reason of the configuration of the teeth and the centering of each about a point upon or adjacent the leading edge of the file, and providing aligned series of notches in spaced relation as shown, the file will perform both roughing and finishing operations upon a single stroke. This follows from the fact that teeth adjacent the leading edge have relatively small shearing angles, the lands adjacent this edge are shorter, and the cutting action is relatively coarse. Toward the trailing edge of the file the shearing angle, i. e., the approximate angle which each land makes with the direction of movement of the file, is much less than at the opposite side, ultimately becoming approximately 37° instead of 90° as along the leading edge, the lands becoming longer and the cutting action much finer. Likewise, along the leading edge of the file the teeth are spaced apart more widely than they are along the trailing edge or, in other words, the file is coarser along its leading edge than along its trailing edge. This is because the teeth are curved about centers on a line parallel to but offset toward the leading edge of the file from the longitudinal axis thereof and naturally converge as the distance from the line of centers increases. Decrease in coarseness of the file from side to side is an important factor in giving it the capacity for roughing and finishing with the same stroke.

Disposition of the series of notches in the man-

ner described likewise tends to prevent too great a lateral movement of the file on its working stroke, in the direction of its leading edge. Naturally, by reason of the general inclinations of the teeth the file will tend to move laterally (upwardly as shown in Figure 1) as it is moved forwardly. By reason of the provision of the inclined notches, and the inclined series of notches, however, this tendency is counteracted to some extent, each notch leaving a small land or uncut portion upon the work as the tooth in which it is formed passes any given point. The pressure of this small land or protuberance against the inclined wall of the notch tends to prevent lateral sliding movement of the file body. Naturally, each such projection is immediately severed by the following tooth but the temporary stabilizing effect is helpful and makes it possible for the operator to move the file more easily along the path which he would naturally give it in filing any piece of work.

Files embodying the invention will, in the usual case, be formed substantially as described and illustrated. It is clear, however, that either edge may be made the "leading" edge, and for special reasons the teeth may be centered on the edge 16 and the lines of notches reversed in direction. When such a file is in use it will be so manipulated that the direction of bodily movement side-wise is also reversed. It will also be apparent to one well acquainted with the use of files that the novel file may be used as a roughing file if moved sidewise, while advancing, with that edge which is normally the trailing edge, in advance.

Having thus described the invention, what is claimed as new and desired to be secured by Letters Patent is:

An elongated double purpose file having a filing surface comprising a multiplicity of arcuate cutting teeth spaced along the length of the file the convex sides of which face toward that end of the file which leads when the file is moved

on its cutting stroke, the centers of curvature of said teeth being spaced from each other along a line substantially coinciding with one edge of said filing surface, and substantially parallel lines of serrations each running through a plurality of said teeth from the trailing end of said file and the edge thereof opposite said one edge at an angle toward said one edge and the leading end of said file, dividing said arcuate teeth into individual tooth cutting sections, so that the tooth sections adjacent said one edge thereof are relatively short, widely spaced and have small angles of shear so as to together constitute an elongated coarse cutting or roughing area, and the tooth sections adjacent the opposite edge of the file are longer, closer together and have larger angles of shear than those of the roughing area and together constitute an elongated surface finishing area, whereby the file when moved forwardly upon a cutting stroke and given a simultaneous lateral movement with the roughing area in advance of the finishing area, will first rapidly remove stock from a given area of a work piece and, during the same stroke, will immediately thereafter finish file such portion.
